AWNING STRUCTURE

Frank Fields, Chicago, Ill., assignor to Enduro Metal Awning Corporation of America, Charles-ton, W. Va., a corporation of West Virginia

Application August 13, 1948, Serial No. 44,115

4 Claims. (Cl. 20—57.5)

1

My invention relates to awnings used in connection with building apertures; such as, windows and doors, and has a special relation to awnings fabricated of metal or rigid materials.

An important object of my invention is to provide an awning of the above-mentioned character which is demountably attachable by means of special attaching brackets, preferably to the trim of a window or door, so that the said awning may be easily and quickly mounted to, or demounted therefrom.

A further object of my invention is to provide a metal fabricated awning, the top apron of which is constructed of awning assembly units to permit individual awnings to be mounted on any width of window or door without the necessity of being custom-made therefor, as is the present practice for such awnings.

A still further object of my invention is to provide a metal fabricated awning, the top apron assembly units of which are comprised of alternate channels and flat strips to give added strength thereto, as well as to make for a handsome, streamlined appearance.

A further object of my invention is to provide a metal fabricated awning, the side aprons of which are constructed of vertical, metal slat strips so arranged to allow the free passage of air therebetween, while at the same time serving as a shade for direct sunlight.

A still further object of my invention is to provide a metal fabricated awning having an awning hood which acts as a seal against the elements, and is so positioned to permit the passage of air currents from below the awning to further prevent the trapping of heated air therein.

A further object of my invention is to provide a metal fabricated awning that may be painted, or enameled, to any color, or combination of colors, and that may be economically manufactured in large quantities.

Other objects and advantages embraced in my invention will be disclosed in the following description and the accompanying illustrations in which like parts are designated by like numerals, and in which:

Fig. 1 is a perspective view of my invention with parts broken away, shown mounted on the trim of a window.

Fig. 2 is an enlarged cross-sectional view of a portion of my invention taken substantially on line 2—2 on Fig. 1, and showing the assembly means of the top apron assembly units.

Fig. 3 is a cross-sectional view of my invention taken substantially on line 3—3 on Fig. 1.

2

Fig. 4 is an enlarged fragmentary cross-sectional view of my invention taken substantially on line 4—4 on Fig. 3.

Fig. 5 is an enlarged perspective view of one of the top apron support brackets comprising an important element of my invention.

Fig. 6 is a perspective view showing the mounting brackets of my invention mounted in place on the trim of a window, and showing the means of attaching my metal fabricated awning thereto, and detaching it therefrom.

Referring to the illustration, my invention is generally designated 7 and consists of a top apron structure 15 having a valance portion 36, side apron structure 39, and a hood element 19.

The said top apron structure 15 consists of end awning assembly units 9 and intermediate awning assembly units 8. The said end awning assembly unit 9 consists of an edging angle 10, having a seamed edge 11, which frictionally holds one of the flanged channel edges 39 of a channel strip 12. The other flanged channel edge 39 is frictionally held by the seamed edge 11 of a flat or slat strip 13 to the other edge of which a dually seamed connector strip 14 connects a second similar, but oppositely formed, flat strip 13'. The intermediate awning assembly units 8 are similar in construction and assembly with the above described end awning assembly units 9, except for the edging angles 10. Strengthening channels 16 and 17 are transversally mounted on the under surface of awning 7, as shown in Figs. 1 and 2, and held by connector strip attaching screws 31 to the connector strips 13.

An awning attaching channel 18 is fastened on the underside at the inner edge of the top of the awning apron 15 by attaching screws 31, as shown in Figs. 1 and 3. The said side aprons 39 are constructed of vertical strips 31, alternately and oppositely, attached to apron assembling channels 32 and 33. The edges 40 of the said strips 31 are flanged, as shown in Figs. 1 and 4, with the strips 31 mounted on the outside of apron assembling channels 32 and 33, being flanged outwardly; whereas the slats 31 mounted on the inside of the said apron assembling channels 32 and 33 are flanged inwardly to provide air spaces 41 therebetween, allowing air currents, designated 43, to flow freely from the confines of awning 7. The said strips 31, however, are so positioned, as shown in Figs. 1, 3 and 4, to prevent direct rays of sunlight from penetrating therethrough and to keep the rain therefrom. The upper side apron assembling channels 32 in assembled position fit within the edging angles

10 on the two ends of top apron 15, as shown in Figs. 1 and 2, and are held thereto by strip attaching screws 37.

The downwardly formed ends of strip channels 12 in the valance portion 36 of the top apron 15 are closed at 44, as shown in Figs. 1 and 3, to give added rigidity to the said valance portion 36.

A number of top apron support brackets 20 are mounted and aligned at spaced intervals, preferably along the top trim of the window or door 29, as shown in Figs. 1, 3 and 6, by bracket attaching screws 21.

An awning hood 19 is attached to hood attaching portion 23 of the said top apron support bracket 20, and is so positioned over the inner end of the top apron 15 to provide an air circulating space 42 therebetween, while serving as weather protection therefor. The said awning hood 19 is provided with an awning hood sealing portion 34 which fits sealably against the trim, or siding, of the building, as shown in Figs. 1 and 3. The outer edge of the awning hood 19 is bent to provide a hood strengthening bead 35.

An adjustable awning holding element 25 is attached to awning holding portion 24 of bracket 20 by means of a screw and nut attaching means 27 through slot means 26. The ends of the adjustable awning holding element 25 are bent to form an awning grip portion 28. The side apron angle attaching brackets 45 are secured to window 29 by attaching screws 21, as shown in Figs. 1, 3, 4 and 6.

My metal fabricated awning 7 is assembled by frictionally engaging the seamed edges 11 of a sufficient number of the intermediate awning assembly units 8 with the two end awning assembly units 9 to provide an awning 7 of the proper window or door width, and the side aprons 30 are attached thereto in the manner hereinabove described.

To mount the said awning 7 on the window 29, the awning attaching channel 18 is slung in the awning grip portions 28 of top apron support brackets 20, and the side aprons 30 are secured to the side apron attaching brackets 45 by attaching screws 38, as shown in Fig. 6. To remove, or demount, my metal fabricated awning 7, it is only necessary to remove the said side apron attaching screws 38 and lift the said awning 7 from the top apron support bracket 20.

The advantages of my metal fabricated awning lie in its ability to be adapted to any window or door width without being custom-made therefor, combined with the extreme simplicity and ease of its mounting thereto and demounting therefrom. To further sum up the advantages of my metal fabricated awning, it will be seen that the alternate channel and strip assembly means of the top apron structure thereof provide the necessary strength and rigidity while adding to the handsome, stream-lined appearance of the awning. The simple attaching means permits the awning to be demounted for cleaning and painting purposes, and the ventilated structure prevents heated air from being trapped therein while serving as protection against the elements and direct sunlight.

It is to be understood that changes may be made in the construction and in the combination and arrangement of the several parts, provided that such changes fall within the scope of the appended claims.

Having thus disclosed and revealed my inven-

tion, what I claim as new and desire to secure by Letters Patent is:

1. A metal fabricated awning structure comprising, an awning including a top apron and side aprons, awning attaching channel means secured to the upper free edge of the said top apron, and top apron support brackets securable to a building structure provided with awning grip portions for removably engaging the said awning channel attaching means, the said side aprons including a fastening channel, and a multiplicity of metal strips having flanged edges secured to the said channel in alternate inverse and oppositely disposed relationship with respect to the said channel, the said flanged edges being in superimposed relationship to afford oblique circulation of air currents, the said top apron including units each consisting of a channel strip having outwardly flanged right and left slat strips each having a seamed edge and a flat edge, a dually seamed connector strip interconnecting the flat edges of the said right and left slat strips, one of the said flanged edges being secured to a seamed edge of one of the said slat strips, an edging angle having a seamed edge secured to one of the said units forming an end awning assembly, and reinforcing channel means rigidly securing the said unit and end awning assembly.

2. A metal fabricated awning structure comprising, an awning including a top apron and side aprons the said top apron including units each consisting of a channel strip having outwardly flanged right and left slat strips each having a seamed edge and a flat edge, a dually seamed connector strip interconnecting the flat edges of the said right and left slat strips, one of the said flanged edges being secured to a seamed edge of one of the said slat strips, an edging angle having a seamed edge secured to one of the said units forming an end awning assembly, and reinforcing channel means rigidly securing the said unit and end awning assembly.

3. A metal fabricated awning structure comprising, an awning including a top apron and side aprons, awning attaching channel means secured to the upper free edge of the said top apron, and top apron support brackets securable to a building structure provided with awning grip portions for removably engaging the said awning channel attaching means, the said awning grip portions being provided with adjusting means to permit securing the said awning structure in spaced relationship to the said building structure to afford ventilating space for the circulation of air currents, said top apron including units each consisting of a channel strip having outwardly flanged right and left slat strips each having a seamed edge and a flat edge, a dually seamed connector strip interconnecting the flat edges of the said right and left slat strips, one of the said flanged edges being secured to a seamed edge of one of the said slat strips, an edging angle having a seamed edge secured to one of the said units forming an end awning assembly, and reinforcing channel means rigidly securing the said unit and end awning assembly.

4. A metal fabricated awning structure comprising, an awning including a top apron, side aprons and a front valance portion, awning attaching channel means secured to the upper free edge of the said top apron, top apron support brackets securable to a building structure provided with awning grip portions for removably engaging the said awning channel attaching means, and awning hood means secured to the

top of the said top apron support brackets, the said awning grip portion being provided with adjusting means to permit securing the said awning structure in spaced relationship to the said building structure to afford ventilating space for the circulation of air currents, the said side aprons including a fastening channel, and a multiplicity of metal strips having flanged edges secured to the said channel in alternate inverse and oppositely disposed relationship with respect to the said channel, the said flanged edges being in superimposed relationship to afford oblique circulation of air currents, the said top apron including units each consisting of a channel strip having outwardly flanged right and left slat strips 15 each having a seamed edge and a flat edge, a dually seamed connector strip interconnecting the flat edges of the said right and left slat strips, one of the said flanged edges being secured to a

5 seamed edge of one of the said slat strips, an edging angle having a seamed edge secured to one of the said units forming an end awning assembly, and reinforcing channel means rigidly securing the said unit and end awning assembly.
